UNITED STATES PATENT OFFICE

PETER CARLSON, OF PROVIDENCE, RHODE ISLAND.

SCREEN.

1,097,300.

Specification of Letters Patent.

Patented May 19, 1914.

Application filed October 7, 1913. Serial No. 793,851.

To all whom it may concern:

Be it known that I, PETER CARLSON, a citizen of the United States, residing at Providence, in the county of Providence and State of Rhode Island, have invented 5 certain new and useful Improvements in Screens, of which the following is a specification.

My invention relates to screens and particularly to metallic screens of an extendible character.

The essential objects of my invention are to provide a window screen which is extendible both vertically and horizontally; and 15 one which is capable of being constructed of light weight and bendable material which will withstand blowing or being pushed from its seat while in use, and to attain these ends in a structure which is inexpensive and easily operable.

To these ends essentially my invention consists in such parts and combinations of parts as fall within the scope of the appended claims.

Figures 1 and 2 are front and end elevations respectively of my novel screen, Fig. 3, a section on line *u u* of Fig. 1, Fig. 4, an enlarged detail of an end portion of one of the guide strips, and Figs. 5, 6, 7, 8 and 9, 25 enlarged sections on lines *v v*, *w w*, *x x*, *y y*, and *z z* respectively.

Like reference characters indicate like parts throughout the views.

In detail the screen comprises two similar 35 frames A, A' for holding the mesh *a*, *a'*, which frames overlap each other at their inner portions. The frame A comprises the upper strip *b* and the lower strip *b'*, and the frame A' has an upper strip *b*² and lower 40 strip *b*³. Upon the inner end portions of the frames A and A' respectively are the marginal strips *c* and *c'* of similar construction. The end strips *d* and *d'* of the respective frames are also of identical construction. It is essential that the material of the 45 described strips should be of thin sheet metal such as enameled tin or tinned sheet-iron, of a bendable character, in order to render the construction substantially light, 50 compact and adaptable to facile engagement with the screen cloth or wire, and with a minimum of fastening agents, and further to facilitate movement of the slidable parts, as well as to avoid the warping of the parts 55 of the frames which occurs in a wooden construction. The strip *b* is formed of sheet

metal bent upon itself to tightly grip the edge of the mesh *a*. Of similar construction is the strip *b'* as shown in Fig. 9 except that the material of the strip is extended and rebent as at *e* forming a downwardly directed tongue *e'*. The strip *c* as shown in Fig. 5 is also bent upon itself to clamp the wire fabric *a* between its sides, and has also near its end an angular bend 60 to form an inturned rib *f*; and a similar rib or flange *f'* is formed upon the strip *c'*, these ribs insuring a close contact of the slideable frames and their wire fabric during any change of position of the parts. The 65 end strip *d* is also bent upon itself to engage between the bent portions of the strip the fabric *a*, but the width of the strip is such that after the described clamping the strip is again bent at a right angle forming 70 a hollow tongue *g* disposed at a right angle to the body of the strip, as shown in Fig. 6. As the strip *d'* is similar in all respects to the described strip *d* a detailed description of the latter is omitted. The strip *b*³ is 75 also bent to clamp the fabric *a'*, and is bent in a U shape forming a longitudinally disposed guide tongue *h* creating a channel *h'* adapted to receive the strip *b'*. The strip *b*² is in detail similar to the described strip 80 *b*³, and its flange *h* serves as a guide to the strip *b* which moves in its channel *h'*. Integral with the upper margins of the strips *b*² and *b*³ are forwardly directed flanges 85 *j*, *j'*, which are adapted to be grasped by 90 the fingers to lift the screen.

The screen is mounted for vertical movement in guides K K fixed by screws or otherwise to the window frame, each guide being similar in construction. These guides K 95 have a body *k* provided with a perforation *k'* to receive a nail or screw by means of which the member K may be attached to the window frame. Upon the forward portion of the guide member is a straight flange *k*² 100 adapted to overlap the strip *d*, and upon the opposite side of the member *k* is an inturned U shaped flange *k*³ adapted to loosely engage and retain the angular flange *g* of the strip *d*. By virtue of the peculiar construction of the inter-engaging members *d* and *K* it will be noted that a substantial engagement is assured against any transverse pressure upon the screen frames by wind or a blow. The members A, A' may be relatively contracted or extended to attach themselves to any size of window by an end pres- 110

sure forcing the strips b and b' to travel in guide strips b^2 , b^3 . The frames may be moved to any desired vertical position in the guide members K by upward pressure upon the flanges j or otherwise, thus the entire screen is adapted to adjustment in two directions.

It will be noted that by the particular construction of guide and cooperating hollow tongues or flanges, the engagement is snug and all wabbling of the parts is prevented.

What I claim is:—

1. In a window screen, the combination of two frames, one frame comprising top and bottom strips provided with U shaped guide flanges, and an end strip provided with an angular flange, the second frame comprising top and bottom strips slidable in the first mentioned strips, and an end strip provided with an angular flange, the top and bottom strips of the second frame being adapted to slide in the U shaped flanges of the first frame, and vertical guide members comprising straight flanges, and U shaped flanges adapted to slidably engage the angular flanges and guides having a straight flange adapted to overlap one of said strips and an inturned U-shaped flange loosely engaging and retaining the angular flange of said strip.

2. In a window screen, the combination

of two frames, one frame comprising horizontal strips provided with U shaped guide flanges, an inner end strip, and an outer end strip provided with an angular flange, the second frame comprising horizontal metal strips slideable in the U shaped guide strips of the first frame, an inner end strip, and an outer end strip provided with an angular flange, and vertical guide members comprising straight flanges, and U shaped flanges adapted to slidably snugly engage the angular flanges.

3. In a window screen, the combination with two frames horizontally disposed relatively and slidably overlapping, the end strip of one of said frames having an angular flange, relatively fixed guide members with a straight flange upon its forward portion to overlap the adjacent end strip of one of said frames and upon the opposite side with an inturned U-shaped flange adapted to loosely engage and retain the angular flange on said strip whereby the frames are held against displacement by transverse pressure upon the frames.

In testimony whereof I affix my signature in presence of two witnesses.

PETER CARLSON.
